UNITED STATES PATENT OFFICE.

FREDERICK W. GORDON, OF PHILADELPHIA, PENNSYLVANIA.

STEAM-ENGINE.

SPECIFICATION forming part of Letters Patent No. 628,089, dated July 4, 1899.

Application filed February 23, 1899, Serial No. 706,471. (No model.)

To all whom it may concern:

Be it known that I, FREDERICK W. GORDON, of Philadelphia, Philadelphia county, Pennsylvania, have invented certain new and useful Improvements in Steam-Engines, of which the following is a specification.

Applications for patent on this invention were filed in Great Britain, France, Belgium, and Germany on October 14, 1898, but at the time of executing the present specification I am not advised of the grant of any patents upon said applications.

This invention pertains to improvements in steam-engines, and it will be readily understood from the following description, taken in connection with the accompanying drawings, in which—

Figure 1 is a side elevation of a steam-engine exemplifying my invention; Fig. 2, a side elevation of the cylinder, parts being in vertical longitudinal section, the portion at the left being through the steam-valves pertaining to the left-hand end of the cylinder in the plane of line *b* of Fig. 4, while the portion to the right is through the exhaust-valves pertaining to the right-hand end of the cylinder in the plane of line *a* of Fig. 4; Fig. 3, a side elevation of the cylinder; Fig. 4, an end elevation of the cylinder; Fig. 5, a side elevation of one of the release-gears; Fig. 6, a vertical section through a portion of the left-hand cylinder-head and through one of the steam-valves, the section being in the plane of line *b* of Fig. 4; and Fig. 7 is a vertical transverse section of valve-cylinder 23 with its valve-piston in place, the follower of the valve-piston being omitted, the section being in the plane of line *c* of Figs. 2 and 6.

In Fig. 2 the valve-pistons are, owing to the smallness of the scale, shown as being unprovided with packing-rings, Figs. 6 and 7 being designed particularly to illustrate the packing system.

The valves are piston-valves working in valve-cylinders in the main cylinder-heads, each cylinder-head having a pair of coupled steam-valves and a pair of coupled exhaust-valves. As the equipment of each main cylinder-head is the same, the description may be in the singular.

In the drawings, 1 indicates the engine-cylinder; 2, its piston; 3, the cylinder-heads,

which will hereinafter be generally referred to in the singular; 4, a steam-chamber formed in the cylinder-head and provided with a suitable inlet; 5, an exhaust-chamber formed in the cylinder-head and provided with a suitable outlet; 6, an exhaust-valve cylinder formed in the cylinder-head, with its axis parallel with that of the engine-cylinder, the inner end of this valve-cylinder being fully open to the engine-cylinder; 7, ports placing valve-cylinder 6 in free and constant communication with exhaust-chamber 5; 8, an enlarged flaring counterbore at the inner end of valve-cylinder 6; 9, a valve-piston working in valve-cylinder 6, its outer or right-hand edge coöperating with the right-hand extremity of counterbore 8, counterbore 8 being longitudinally ribbed to provide bearing for the valve-piston; 10, a second exhaust-valve cylinder parallel with valve-cylinder 6; 11, ports near the inner end of valve-cylinder 10 and placing it in communication with exhaust-chamber 5; 12, a valve-piston working within valve-cylinder 10, its inner or left-hand end serving to cover and uncover ports 11; 13, a rock-shaft journaled on the cylinder-head, its axis being at right angles to the common axial plane of valve-cylinders 6 and 10; 14, a rocker-arm fast on this rock-shaft; 15, valve-stems connecting valve-pistons 9 and 12 with arm 14; 16, an arm fast on the rear end of rock-shaft 13, the term "rear" being relative to Figs. 1, 2, and 3 as being front elevations; 17, a rock-shaft journaled across the top of the engine-cylinder; 18, a wrist-plate fast on the front end of this shaft; 19, a rod linked to wrist-plate 18 and serving to transmit operative motion to the wrist-plate and its rock-shaft; 20, a wrist-plate on the rear end of rock-shaft 17, and 21 links connecting wrist-plate 20 with arms 16.

Valve-pistons 9 and 12 are shown in about line-and-line position just beginning to open. The movement of wrist-plate 20 will obviously cause valve-piston 9 to move to the left and valve-piston 12 to move to the right, such movement of the valve-pistons causing valve-piston 12 to uncover ports 11 and permit exhaust to take place from the engine-cylinder through valve-cylinder 10 and ports 11, while valve-piston 9 will be projected farther into the engine-cylinder and permit exhaust to

take place from the engine-cylinder through counterbore 8 and ports 7. At proper time wrist-plate 20 will move the valve-pistons to position of closure and then to position of full lap, with the ends of the valve-pistons about flush with the inner face of the cylinder-head. The two valve-pistons are of equal area and connected to rocker 14 at equal distances from the axis of the rocker, the two valves being balanced in all respects, their actuation calling only for the power necessary to overcome their mechanical friction.

Proceeding with the drawings, 22 indicates a steam-valve cylinder disposed in the cylinder-head across steam-chamber 4, this valve-cylinder being ported and counterbored similar to exhaust-valve cylinder 6; 23, a steam-valve cylinder similar to exhaust-valve cylinder 10 and forming a companion to valve-cylinder 22; 24, a valve-piston working in valve-cylinder 22; 25, a valve-piston working in valve-cylinder 23; 26, a rocker-arm connected with the stems of valve-pistons 24 and 25; 27, the shaft of rocker-arm 26, valve-cylinders 22 and 23, valve-pistons 24 and 25, arm 26, and shaft 27 pertaining to the steam-valve system and being alike to corresponding parts of the exhaust-valve system previously described, except that rock-shaft 27 in the case of the steam-valves projects from its rocker 26 to the front of the engine-cylinder; 28, an arm fast on the front end of rocker-shaft 27 and having a tooth to be engaged by a pawl; 29, a dash-pot of usual construction; 30, a dash-pot rod connected with arm 28 and serving to pull arm 28 downward or in direction corresponding with closing motion of the steam-valves; 31, an arm with its axis coinciding with that of rock-shaft 27, but loose with reference to that rock-shaft and its arms 26 and 28; 32, links connecting arms 31 with wrist-plate 18; 33, a pawl carried by arm 31 and adapted to engage the tooth of arm 28 and move arm 28 in direction corresponding with opening motion of the steam-valves; 34, a cam-arm with its axis coincident with that of rock-shaft 27; 35, a trip-arm fast with pawl 33 and engaging the cam of cam-arm 34; 36, links connecting cam-arms 34 with the engine-governor, and 37 a spring carried by arm 31 and serving to press pawl 33 to operative relationship to the tooth of arm 28.

The steam-valve pistons 24 and 25 have operative motion, as previously described in connection with the exhaust-valve pistons; but in the case of the steam-valves they are opened by release-gear and closed by the dash-pots. Referring to Fig. 2, arm 31 will move to the right, its pawl causing the steam-valves to open in an obvious manner. When trip-arm 35 rides up on the projection of cam 34, the pawl will be released and the dash-pot will suddenly close the steam-valves. The release-gear is similar to that at present employed on engines of the Corliss type, and the adjustment of cams 34, and consequently the point of cut-off, is similarly under the control of the engine-governor.

Referring to Fig. 2, as the engine-piston 2 moves to the right the valve-piston 24 in the course of its opening motion follows it and projects into the engine-cylinder, while in closing and going to position of full lap it withdraws from the engine-cylinder. Regarding all of the valves it is to be observed that they are truly balanced, that they bring about a minimum of clearance, and that the system results in the minimum of metal surface exposed to the steam in excess of the metal surface represented by the bore and end walls of the main cylinder.

Proceeding with the drawings, 39 indicates the engine-shaft; 40, the eccentric; 41, the crank; 42, the governor; 43, a rocker, to which the forward end of rod 19 is connected, and 44 the eccentric-rod connected with rocker 43.

The governor in its construction and in its mode of connection with and operation upon cam-rods 36 may be the same as in ordinary engines of the Corliss type.

Referring to Fig. 2, it is to be observed that the valvular function of valve-pistons 12 and 25 is performed by what might be called the "front ends" of the pistons, while in the case of valve-pistons 9 and 24 the valvular function is performed by the rear ends of the pistons. The ends of the valve-pistons which have valvular performance should be provided with suitable packing-rings, and a satisfactory form of packing will be described. Valve-pistons 9 and 24 have, it will be observed, supplementary pistons working in the valve-cylinders; but they are without valvular office, their purpose being merely to increase the bearing of the valve-pistons, a result accomplished in valve-pistons 12 and 25 by making the pistons long. In the case of the upper valve-pistons they are, in effect, long, but of spool-shape. The valve-pistons are solid in the sense that steam does not pass through them.

Figs. 6 and 7 illustrate a preferred system of packing for the valve-pistons, illustrated in connection with valve-piston 25. In these figures of the drawings, 45 indicates the bridges or ribs of the ports in the wall of the valve-cylinder, the inner surfaces of these bridges being flush with the bore of the valve-cylinder; 46, an L-shaped packing-ring fitting in a rabbet at the end of the valve-piston; 47, a rectangular ring fitted in the angle of ring 46, the outer end surface of ring 47 forming the functional end of the valve-piston; 48, a follower on the valve-piston, forming the outer wall for the circumferential groove containing the packing-rings, the follower being of less diameter than the valve-cylinder, so as to leave the outer face of ring 47 free to form the valvular element of the valve-piston; 49, a cut in ring 47, causing that ring to be an open ring capable of expansion; 50, a cut in ring 46, causing that ring also to be an open expansion-ring, cut 49 traversing one of bridges 45 while

cut 50 traverses another one of the bridges, and 51 a dowel in the valve-piston and packing rings and serving to maintain the relationship of cuts 49 and 50 to each other and 5 to the bridges which they traverse. This form of packing-rings is not new, but its arrangement and mode of operation possess certain points of novelty. In Fig. 6, assume the valve-piston to be moved to the right to position of closure. In such case the left-hand face of the packing-ring will be toward the greater pressure—that represented by steam-chamber 4—which pressure will always be as great as and generally in excess of that in the 15 steam-cylinder. That face of the packing which is formed entirely by ring 46 is to be disposed toward the greater pressure and that face of the packing formed by the two rings jointly being toward the lesser pressure. If 20 there be any leakage whatever, it will be from the greater toward the lesser pressure, and consequently steam under the greater pressure will find its way inwardly through cut 50 into the interior of ring 46 and cause the 25 expansion of both rings. Such packing-rings may be applied to all of the valve-pistons, so that a face of the packing will form the functional edge of each valve-piston, that face of the packing formed wholly by the L-shaped 30 ring being placed toward the greater pressure—that is to say, away from the engine-cylinder in the case of the steam-valves and toward the steam-cylinder in the case of the exhaust-valves.

35 I claim as my invention—

1. In a steam-engine, the combination, substantially as set forth, of an engine-cylinder, heads therefor each having a steam-chamber and an exhaust-chamber, a pair of exhaust-40 valve cylinders and a pair of steam-valve cylinders in each of said heads and having their inner ends open to the engine-cylinder, a closed valve-piston in each of said valve-cylinders, a rocker pivoted at each of said 45 cylinder-heads and connecting the exhaust-valve pistons in that head, positive mechanism connecting the engine-shaft with said rockers and serving to give said exhaust-valve pistons their opening and closing motions, a rocker pivoted at each of said cylinder-heads and connecting the two steam-valve pistons of that head, positive mechanism connecting the engine-shaft with said last-mentioned 50 rockers and serving to give said steam-valve pistons their opening motions, release devices 55 interposed in said last-mentioned mechanism, and dash-pots connected with said steam-valve pistons and serving to give them their closing motions.

60 2. In a steam-engine, the combination, substantially as set forth, of a steam-cylinder, heads therefor containing each a steam-cham-

ber and exhaust-chamber, a pair of exhaust-valve cylinders and a pair of steam-valve cylinders in each of said cylinder-heads and open 65 to the engine-cylinder, closed valve-pistons in each of the valve-cylinders, a rock-shaft disposed across the engine-cylinder, a wrist-plate on each end of the rock-shaft, mechanism for transmitting motion from the engine-shaft to said wrist-plates, a rocker pivoted at the cylinder-head and connecting the two steam-valve pistons of that head, a rocker pivoted at each cylinder-head and connecting the two exhaust-valve pistons of that head, 70 connections between one of said wrist-plates and the rockers of the exhaust-valve pistons, and connections between the other of said wrist-plates and the steam-valve pistons.

3. In a steam-engine, the combination, substantially as set forth, of an engine-cylinder, heads therefor provided each with a steam-chamber, a pair of steam-valve cylinders in each of said heads and open to the engine-cylinder, a valve-piston in each of said valve-cylinders, a rocker pivoted at each cylinder-head and connecting the valve-pistons of that head, a toothed arm connected with each of said rockers, an actuating-arm loose at each of said rockers, mechanism connecting the 80 engine-shaft with said actuating-arms and serving to oscillate them, a pawl carried by each of said actuating-arms and adapted to engage the appropriate toothed arms, cam-arms mounted at said actuating-arms and 85 adapted to cause the release of the pawls, a governor, and mechanism connecting said governor with said cam-arms.

4. In a steam-engine, the combination, substantially as set forth, of an engine-cylinder, 100 an eccentric on the crank-shaft of the engine, a pair of ported steam-valve cylinders and a pair of ported exhaust-valve cylinders in each head of the engine-cylinder and having their inner ends open thereto, a closed valve-piston 105 in each of said valve-cylinders, a rocker for each pair of valve-pistons and connecting the two valve-pistons of the pair, and connections between said rockers and said eccentric.

5. In a steam-engine, the combination, substantially as set forth, of an engine-cylinder, 110 an eccentric on the crank-shaft of the engine, a pair of ported valve-cylinders in each head of the engine-cylinder and having their inner ends open to the engine-cylinder, a closed 115 valve-piston in each of said valve-cylinders, a rocker mounted at each cylinder-head and connecting the two valve-pistons thereof, and connections between said eccentric and said rockers.

FREDERICK W. GORDON.
